UNITED STATES PATENT OFFICE.

REINHARD J. WILKENS, OF BALTIMORE, MARYLAND.

GAME-COUNTER.

SPECIFICATION forming part of Letters Patent No. 643,929, dated February 20, 1900.

Application filed April 15, 1899. Serial No. 713,179. (No model.)

To all whom it may concern:

Be it known that I, REINHARD J. WILKENS, a citizen of the United States, residing at Baltimore, in the State of Maryland, have invented certain new and useful Improvements in Game-Counters; and I do hereby declare the following to be a full, clear, and exact description of the invention, such as will enable others skilled in the art to which it appertains to make and use the same.

This invention relates to a new game-counter designed more especially to be used with a game of cards called "scat." It is not necessary here to enter into a detailed description of this game, but only so much of it will be described as is necessary for the manipulation of the counter.

In the annexed drawings Figure 1 represents a plan view of the device; Fig. 2, a transverse section taken on the line xx , Fig. 1.

In the drawings, the letter A represents a plate of any suitable material, preferably rectangular, but having at the top a curved projection B. In the plate A there are made five slots a , a' , a^2 , a^3 , and a^4 . The three slots a , a' , and a^2 are made substantially the width of the plate A. The slots a^3 and a^4 occupy about half the width of the plate. In these slots are placed double-headed indicators c , c' , c^2 , c^3 , and c^4 . These indicators have a head on each side of the plate A and a stem C, which fits into the slot of the plate. As indicated, the upper portion of these indicators may be in the shape of a button, an arrow, or a hand.

The surface of the plate A above the slot a is spaced off in nine equal spaces and is numbered from "1" to "9" in order. The surface of the plate between the slots a and a' is spaced off in nine equal spaces and is numbered from "10" to "90" in order. The surface of the plate between the slots a' and a^2 is spaced off in nine equal spaces and is numbered from "100" to "900" in order. The surface of the plate A between the slot a^2 and the slot a^3 is divided into three spaces and numbered from "1,000" to "3,000" in order. Above the slot a^4 the words "Plus" and "Minus" are placed with sufficient space between them. The curved projection B has near its periphery a curved slot b , in which rests an indicator b' . Leading from the center of this curved projection B are three ar-

rows pointing to the three numbers "1," "2," and "3."

In using this device for counting the indicators are shoved to the zero end of the plate—that is, to the left-hand end of each slot. As the game progresses and points are made the indicators are slid along the slots, so as to mark or denote the number of points made. As, for example, if at any time the number of points made by one player amounts to two thousand six hundred and forty-three the indicator c^3 would rest at "2,000," indicator c^2 at "600," indicator c' at "40," and the indicator c at "3." With any increase in the number of his points the indicators would be adjusted to denote such increase. As, for example, should he gain forty-six more points in the next hand the indicator c' would be moved up to "80" and the indicator c up to "9." As the number of points added exceeds the number on any given line the indicator of that line is moved back to zero and the indicator of the next succeeding line is moved up in proportion to the increment. As thus described the device may be used not only for the game of scat, but also for various other games of cards; but what peculiarly adapts this counter for the game of scat is the fifth indicator. In this game the counting is not only done on the plus side, but also upon the minus. In this game the "trump" is made by one of the players, who "bids" so many "points" to have the privilege of making the trump. If he wins a hand, he makes as many points as his hand is "worth;" but if he fail to make the number of points which he has bid he loses that number of points and goes backward to that amount. It not infrequently happens in this game, either at the outset or after the game has progressed, that a player loses so many points that he is on the minus side of the game and worse off than nothing. With a counter such as shown in the drawings this condition of the player is exactly indicated. If points are to be credited to a player, the indicator c^4 is put at the "Plus" mark. If, however, on the other hand, there are points charged against him, the indicator is to be placed at the "Minus" mark. In this way the condition of the player is accurately and clearly fixed without any danger of dispute. Whenever the player shall

have recovered the lost points and is on the plus side, the indicator c^4 is moved from minus to plus.

The players, who in seat are three in number, are to be numbered "1," "2," and "3." Each player is provided with one of these counters, and as each player has the deal the indicator b' is to be moved in the slot b and placed at the number of the player who is 10 dealing.

With a device such as this each player's counter not only indicates his position in the game, but all of the counters indicate the player who has last dealt, so that their agreement on this point prevents any dispute as to who has the next deal. This counter may have suitable feet or legs D on which to rest. 15

Having described my invention, what I claim is—

20 As a new article of manufacture, a game-

counter, consisting of the plate A, provided with the slots a a' a^2 a^3 and a^4 , located as shown, and having the numbers from "1" to "9" above the slot a ; the numbers from "10" to "90" above the slot a' ; the numbers from 25 "100" to "900" above the slot a^2 , and the numbers from "1,000" and up above the slot a^3 , and the words "Plus" and "Minus" just above each end of the slot a^4 , and the indicators c c' c^2 c^3 and c^4 , one in each slot, and 30 the top projection B having the slot b in which is an indicator b' the arrows and a different number for each arrow, as shown.

In testimony whereof I affix my signature in presence of two witnesses.

REINHARD J. WILKENS.
